US00D815746S

(12) **United States Design Patent** (10) **Patent No.:** **US D815,746 S**
(45) **Date of Patent:** **** Apr. 17, 2018**

(54) **ELECTRODE**

(71) Applicant: **IMPETO MEDICAL**, Paris (FR)

(72) Inventors: **Mathieu Seval**, Les Clayes Sous Bois (FR); **Nicolas Bocquet**, Chatillon (FR)

(73) Assignee: **Impeto Medical**, Paris (FR)

(**) Term: **15 Years**

(21) Appl. No.: **29/595,026**

(22) Filed: **Feb. 24, 2017**

Related U.S. Application Data

(62) Division of application No. 29/563,266, filed on May 3, 2016, now Pat. No. Des. 796,681.

CLAIM

The ornamental design for electrode, as shown and described.

DESCRIPTION

FIG. 1 is a perspective view of an electrode showing our new design;

FIG. 2 is a top view thereof;

FIG. 3 is a bottom view thereof;

FIG. 4 is a back view thereof;

FIG. 5 is a front view thereof;

FIG. 6 is a right side view thereof;

FIG. 7 is a left side view thereof; and,

FIG. 8 is a perspective view of the electrode in a second position of use wherein an interior portion is shown in a second position of use, the rear surfaces of the interior portion are comprised of unclaimed subject matter.

(Continued)

The broken lines constitute environment and, thus, unclaimed subject matter.

1 Claim, 6 Drawing Sheets

(58) Field of Classification Search

CPC 19/50; G01G 21/28; G01G 21/3735; G01G 23/01
